UNITED STATES PATENT OFFICE.

HAROLD J. LE VESCONTE, OF CHICAGO, ILLINOIS, ASSIGNOR TO UNION SPECIAL MACHINE COMPANY, OF CHICAGO, ILLINOIS, A CORPORATION OF ILLINOIS.

GLOVE-SEWING MACHINE.

Application filed June 11, 1925. Serial No. 36,391.

The invention relates to new and useful improvements in sewing machines, and more particularly to a sewing machine which is especially adapted for stitching around sharp curves such as tipping gloves and the like.

An object of the invention is to provide a machine having a single needle, a feeding mechanism and a presser foot, with means for raising the presser foot from the material, while the needle is still in the material and before the feed takes place, so that the material may be swung on the needle as a pivot to aid in the directing of the material in a sharp curved path.

15 A further object of the invention is to provide a sewing machine having a clamp feed with a presser foot lifting mechanism of the above type, wherein the foot is raised when the upper feed dog is lifted from the 20 material while the needle is still in the material, so as to completely relieve the material, whereby it may be swung on the needle as a pivot to aid in stitching around sharp curves.

25 These and other objects will in part be obvious and will in part be hereinafter more fully disclosed.

In the drawings which show by way of illustration one embodiment of the invention—

Figure 1 is a rear view of a sewing machine embodying my improvements;

Fig. 2 is a view partly in section and partly in end elevation from the needle end of 35 the sewing machine;

Fig. 3 is a front view of a portion of the machine, the work support being removed;

Fig. 4 is an enlarged detail view showing 40 the upper feed dog and foot raised so that the material may be swung on the needle as a pivot, and

Fig. 5 is a plan view of the work support and the parts immediately above the same, and showing the preferred form of edge 45 guide used in connection with my machine.

The invention is directed broadly to a sewing machine having a single needle, and a complementary stitch forming mechanism cooperating therewith. The machine is also provided with a feeding mechanism which is 50 preferably in the form of a clamp feed, that is, including an upper and a lower feed dog which engage the material simultaneously and move it a stitch length. This renders the

machine especially adapted for operating upon leather. The machine is also provided with a presser foot which cooperates with the feeding mechanism and the needle in the manipulation of the material and the holding of the material for the forming of the stitches. 55 In addition, the machine includes an automatic means for raising the presser foot slightly from the material at a time when the upper feed is lifted a slight distance from the material, and while the needle is still in the material, so that the material may be turned on the needle as a pivot to aid in the directing of the material in a very sharp curved path. This is especially useful in the sewing of gloves and the tipping of the fingers where the line of stitches following around the finger tip must be laid in a very sharply curved line.

Referring more in detail to the drawings, my improved machine includes an ordinary 75 bed plate 1 carrying a work support 2, also a standard 3, having an overhanging arm 4. Mounted to reciprocate in this overhanging arm 4 is a needle bar 5 carrying a single needle 6. The needle bar is reciprocated by 80 means of a needle lever 7 which is connected to the needle bar by a link 8. Cooperating with the needle 6 beneath the work support is a thread carrying looper 9 which is pivotally carried by a looper rocker 10, and which 85 is oscillated by means of a link 11. The looper rocker is also moved so as to give to the looper a needle avoiding movement, while the link 11 oscillates the looper into and out of the needle thread loop. The material is 90 fed across the work support 2 by the feeding mechanism which includes a lower feed dog 12 and an upper feed dog 13. The lower feed dog 12 is carried by a feed bar 14 pivoted to a feed rocker 15 from which the feed bar is 95 moved back and forth, and thus a feeding movement imparted to the feed dog 12. The feed bar is raised and lowered by the usual eccentric 16 carried by the main shaft 17 (see Fig. 3). The upper feed dog 13 is mounted 100 on a bracket 18. Alongside of the feed bar 14 is an auxiliary feed bar 19 (see Fig. 3), which auxiliary feed bar is pivoted to the same feed rocker as the main feed bar 14 and is moved back and forth by the feed rocker 105 15. The bracket 18 is secured to this auxiliary feed bar 19 by means of screws 20. The shank 13a of the upper feed dog extends be-

neath the cloth plate and is secured to this bracket 18 by means of a screw 21 which passes through a slot 22 in the shank 13^a. This auxiliary feed bar 19 is raised and lowered by an eccentric 23 on the main shaft 17. This eccentric 23 is so set relative to the eccentric 16, that the upper feed bar is raised, lifting the upper feed dog from the material when the lower feed dog is lowered from engagement with the material. Likewise, when the lower feed dog is raised into engagement with the material, the upper feed dog is lowered so as to clamp the material, and while the material is clamped by the two feed dogs, 15 it is moved a stitch length.

The above-described feeding mechanism is shown in detail in the patent to Woodward #591,517, granted October 12, 1897, and a more detail description is not thought necessary. It is only essential to the present invention, in that it is representative of a clamp feed which is especially useful when operating upon leather material.

The material is held on the work support by a presser foot 24 carried by a presser bar 25. This presser bar 25 is mounted on the head at the end of the overhanging arm 4 so that it may be moved up and down in the head. A leaf spring 26 of the usual type bears on an arm 27 secured to the presser bar 25 and yieldingly holds the presser foot pressed down on the work support. The usual guide bar 25^a is also mounted in the head and connected to the main presser bar 25 by the arm 28. Whenever the presser foot is raised, this guide bar 25^a is also raised therewith. On the lower end of the guide bar 25^a is a bracket 29 which is L-shaped, and the lower member thereof extends underneath the lug 30 attached to the shank of the upper feed dog. The purpose of this angle bracket 29 is for lifting the upper feed dog if it is on the material when the presser foot is raised by means of the foot controlled lever 31. The auxiliary feed bar 19 is spring pressed on to the eccentric 23 and can be lifted therefrom so as to permit the upper feed dog to be raised. This occurs only when it is desired to place the material between the feed dogs or remove the material that is clamped by the feed dogs.

At the back of the machine, there is a cross shaft 32 mounted in suitable lugs 33, 33. This cross shaft is provided with a forwardly projecting arm 34 on the forward end thereof. This arm 34 extends underneath the collar 35 fixed to the main presser bar 25. Also secured to the cross shaft 32 is an arm 36. This arm has an arc-shaped slot 37 formed therein in which is adjustably mounted a stud 38. On the main shaft 17 there is an eccentric 39. An eccentric strap 40 cooperates with this eccentric 39 and a link 41 is rigidly connected to the eccentric strap. It is also connected to 35 the stud 38 so that as the main shaft ro-

tates, the link 41 will cause the cross shaft 32 to oscillate, and the extent of oscillation imparted to the shaft depends upon the adjustment of the stud 38. When the cross shaft 32 is oscillated, it will swing the arm 34, and this will raise the main presser bar and the main presser foot 24 from the material. It is understood, of course, that this main presser bar is located at one side of the top feed as clearly shown in Fig. 3 of the drawings. It does not cooperate with the lower feed, but does hold the material on the work support so as to insure the material being stripped from the needle, and also holds the material clamped against the work support at the time 80 the stitch is being set. The eccentric for lifting the presser foot is so timed that the foot is lifted from the work support and the material when the upper feed dog is descending to clamp the material for feeding it, and when 85 the needle is on its up stroke. There is a time, therefore, when the presser foot is lifted from the material, the upper feed dog is also raised from the material, and the needle is in the material on its up stroke. At this time, the operator may quickly swing the material on the needle as a pivot, and thus cause a very sharp turn to be made of the material. The material is entirely free of any clamping action of either the foot or the feed dogs at this time 90 when the needle is in it, so that it can be turned freely thereon. Associated with this presser foot is an edge guiding device which is shown in detail in Fig. 5 of the drawings. This edge guiding device has a head 42 which is located directly opposite to the needle 6. This head bears against the side face of the presser foot 24. Said head is carried by a rod 43 mounted in a bracket 44, and a spring 45 yieldingly forces the rod to the left as 95 viewed in Fig. 5, and against the presser foot. The rod may be retracted by means of a lever 46. The head is just above the face of the cloth plate, and therefore, the edge of the material as it is being stitched will be guided by said head. This insures that the line of 100 stitching shall be properly spaced from the edge of the material. The head has a rounded face as clearly shown in Fig. 5, which enables the material to be turned for stitching 105 in a curved path.

By the use of the edge guide shaped and positioned as above noted, the article operated upon may be turned in a relatively sharp curve, and at the same time, the line of stitches 110 which are being formed, maintained at a predetermined distance from the edge of the fabric. This machine is especially adapted for tipping the fingers of gloves and the like, where it is essential that the line of stitches 115 shall be a uniformed predetermined distance from the edge of the leather.

It is obvious that other ways of raising the presser foot when the upper feed is free from the material and while the needle is in the 120

material, may be utilized, without departing from the spirit of the invention as set forth in the appended claims.

Having thus described the invention, what I claim as new and desire to secure by Letters-Patent, is—

1. A sewing machine including in combination, a work support, a needle bar carrying a single needle, means for reciprocating said needle bar, complementary stitch forming mechanism cooperating therewith, a feeding mechanism including an upper feed dog for feeding the material, a presser foot, and means independent of the feeding mechanism and the needle bar reciprocating means for automatically lifting the presser foot when the upper feed dog is free from the material and while the needle is still in the material, so that the material may be swung about the needle as a pivot.

2. A sewing machine including in combination, a work support, a needle bar, means for reciprocating said needle bar, a single needle carried thereby, complementary stitch forming mechanism cooperating therewith, a feeding mechanism including a lower feed dog and an upper feed dog cooperating to clamp and feed the work, a presser foot alongside of said upper feed dog and having a throat through which the needle passes, automatic means independent of the feeding mechanism and needle bar reciprocating means for raising the presser foot when the upper feed dog is free from the material and while the needle is still in the material whereby said material may be turned on the needle as a pivot to

direct the line of stitching in a sharply curved path.

3. A sewing machine including in combination, a work support, a reciprocating needle bar, a single needle carried thereby, a feeding mechanism including a feed dog engaging the upper face of the material, a presser foot alongside of said feed dog, a main shaft beneath the work support, an eccentric on said main shaft, and devices actuated by said eccentric for automatically raising the presser foot when the feed dog is free from the material and while the needle is in the material to aid in the forming of the line of stitching in a sharply curved path.

4. A sewing machine including in combination, a work support, a reciprocating needle bar carrying the needle, a feeding mechanism including an upper and a lower feed dog for clamping and feeding the material, a presser foot, means for automatically raising the presser foot when the upper feed dog is moved downwardly to engage the material and before the feeding action takes place, and while the needle is still in the material, so that said material may turn on the needle as a pivot to direct the feed in a sharply curved path, and a yielding edge guide located alongside of the presser foot close to the needle for guiding the edge of the material, said edge guide having its surface engaging the material sharply curved so as to properly guide the edge of the material as the material travels in a sharply curved path.

In testimony whereof, I affix my signature.

HAROLD J. LE VESCONTE.
